CLAIM

The ornamental design for a display screen with a set of icons, as shown and described.

DESCRIPTION

FIG. 1 is a front view of a first icon belonging to the claimed set of icons showing the new design;

FIG. 2 is a front view of a second icon belonging to the claimed set of icons showing the new design;

FIG. 3 is a front view of a third icon belonging to the claimed set of icons showing the new design;

FIG. 4 is a front view of a fourth icon belonging to the claimed set of icons showing the new design; and,

FIG. 5 is front view of a fifth icon belonging to the claimed set of icons showing the new design.

The broken lines of uneven length depict portions of the display screen and form no part of the claimed design.

1 Claim, 5 Drawing Sheets
